UNITED STATES PATENT OFFICE.

JESSE H. SROFE, OF KOKOMO, INDIANA.

DESIGN FOR A WIRE FENCE.

SPECIFICATION forming part of Design No. 28,500, dated April 19, 1898.

Application filed December 7, 1897. Serial No. 661,112. Term of patent 7 years.

To all whom it may concern:

Be it known that I, JESSE H. SROFE, a citizen of the United States, residing at Kokomo, in the county of Howard and State of Indiana, have invented and produced a new and original Design for Wire Fences, of which the following is a specification, reference being had to the accompanying drawings, forming a part thereof, in which—

Figure 1 is an elevation of a fence-panel, showing my new design; and Fig. 2 is a detail view of one of the pickets.

As shown in the drawings, the leading or material feature of my design consists of the fence having the several horizontal or cross strands C, C', C², and C³, and the pickets A, having the curved tops B, which overlap, as shown, above the strand C, have the parallel portions B' between the strands C and C', the inclined portions B², crossing each other between the strands C' and C² and between the strands C² and C³, and the lower end portions, which diverge below the lower strand C³, such

lower portions being arranged in pairs and the portions of each pair diverging, as shown. 25

The pickets and the cross-strands C, C', C², and C³ present the appearance of twisted wire, giving the panel and pickets an appearance producing the effect of a fabric.

In the fence-panel the portions B³ of one picket extend on lines parallel to and nearly in alinement with one of the portions B² of the next picket, the several pickets forming series of diamonds D and half-diamonds D' by the crossing of the portions B² and the portions B³, as shown in Fig. 1. 30 35

Having described my invention, what I claim as new, and desire to secure by Letters Patent, is—

The design for a wire fence as herein shown 40 and described.

JESSE H. SROFE.
